(57) **CLAIM**

The ornamental design for a camera bracket to connect riflescope, as shown and described.

DESCRIPTION

FIG. 1 is a front elevational view of a camera bracket to connect riflescope showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, left and front perspective view thereof;

FIG. 8 is a top, right and rear perspective view thereof;

FIG. 9 is a bottom, right and rear perspective view thereof; and,

FIG. 10 is bottom, left and front perspective view thereof.
